UNITED STATES PATENT OFFICE.

ALFRED H. WAIT, OF LINCOLN, KANSAS.

GARMENT-VENTILATING APPLIANCE.

1,263,632.

Specification of Letters Patent. Patented Apr. 23, 1918.

Application filed April 9, 1917. Serial No. 160,725.

To all whom it may concern:

Be it known that I, ALFRED H. WAIT, a citizen of the United States, residing at Lincoln, in the county of Lincoln and State of Kansas, have invented certain new and useful Improvements in Garment-Ventilating Appliances; and I do hereby declare the following to be a full, clear, and exact description of the invention, such as will enable others skilled in the art to which it appertains to make and use the same.

This invention relates to means or devices for rendering more comfortable a person's clothing during warm weather and has for an object the provision of an appliance specifically designed to be used in connection with a blouse or analogous garments for holding the bottom edge portion thereof in spaced relation to the garment or garments therebeneath. By this arrangement there is permitted a free circulation of air upon and about those portions of the body which usually receive the least, and as a result a material reduction in the temperature about the body is secured.

It is further a purpose of the present invention to provide a means of this nature that is of an extremely simple and economical construction, and which in addition may be quickly and conveniently attached and detached.

With the above and other objects of similar nature in view, the invention consists in the construction, combination and arrangement of parts, set forth in and falling within the scope of the appended claim.

In the drawing:

Figure 1 is a section through the lower and upper portions of a blouse and trousers respectively, with the invention associated therewith,

Fig. 2 is a horizontal section taken on the line 2—2 of Fig. 1,

Fig. 3 is a detail section through one of the spacing devices and the related portions of the garments, and

Fig. 4 is a perspective view of one of the spacing devices detached.

Referring now more particularly to the accompanying drawing, there is shown the lower portion of a blouse 5, the bottom edge of which is provided with a heading 6 having drawn therethrough a flexible band or tape 7 that is starched or otherwise suitably stiffened. There is also conventionally illustrated the upper portion of a pair of trou-

ers 8, the position thereof with respect to the blouse being that normally assumed when properly adjusted upon the body of the wearer. It will be noted that the lower 60 portion of the blouse is of a diameter greater than the waist-band of the trousers and that its marginal edge has been folded inwardly to give to the blouse the requisite fullness.

It will also be noted that the heading 6 65 of the blouse is disposed in spaced relation to the trousers, the stiffening band 7 serving with the elements to be described, in preserving such spacing for the full circumference of the blouse. 70

The invention comprises a plurality of spacing devices 9 identical in construction and similarly applied at spaced intervals between the blouse and trousers as clearly illustrated. As above stated these spacing devices 75 are identical in all respects and a description of one will therefore suffice for all.

Each of the devices 9 consists of a strip of suitable resilient material formed to produce an arcuate bow 10 between its ends. 80 At one end of this bow, there is a straight portion of the strip, which extends tangentially to the bow, in the form of a leg A, while at the other end of the bow, there is a straight portion of the strip which extends outwardly from the bow at an angle and in a line intersecting the arc of the bow, thus forming a second leg B, lying in a plane parallel with the leg A and projecting somewhat therebeyond, so that when 90 the complete device is disposed in a vertical position, with the legs directed downwardly, the leg B will extend below the leg A as shown particularly in Fig. 3 of the drawings. 95

Each of the legs A and B is provided adjacent its end with outwardly directed spaced ears 11 formed integrally with the strip and provided with transversely alined openings. The terminals of said legs are furthermore directed outwardly at substantially right angles and have their end edge portions serrated to provide suitable gripping jaws 13. These extremities of the legs of the strip constitute corresponding elements of a pair of spring pressed clasps 14, 100 the other elements thereof being in the form of plates 15 having integral ears 16 pivoted to the corresponding ears 11 and provided with serrated jaws 17 coöperating with the jaws 13. The opposite ends of the plates 110 15 from the jaws 17 are in the nature of finger pieces by which the clasps are manipu-

lated, while springs 18 are interposed between said plates and the legs of the strip to maintain the jaws normally in gripping relation.

5 In applying the spacing devices, the clasps carried by the shorter of the legs are engaged with the heading 6 of the blouse while those carried by the longer of the legs are engaged with the band of the trousers 8. The bottom edge of the blouse is in this manner effectually held in spaced relation to the trousers and thus permits of a free circulation of air around and upon the body of the wearer. However, by reason of the resilient nature of the bow 10, movement of the clasps toward and away from each other is permitted, an encircling pressure serving to compress the legs of the strip while the latter will assume their normal position when such pressure is removed. The particular formation of the bow 10 and its legs provides for a yielding resistance to downward movement of the edge of the blouse as well as inward movement thereof, as will be understood.

10 15 20 25

By the present invention there is provided an extremely simple, effectual and economi-

cal arrangement capable of rendering clothing much more comfortable to the wearer during warm weather by materially reducing the temperature around the body through the medium of ventilation and free circulation of air.

What I claim is:—

A device for supporting the lower edge of a blouse or similar garment and for holding such edge in spaced relation to the garment therebeneath, consisting of an arcuate resilient bow having straight legs at its ends, one of said legs merging into the bow at a tangent thereto and the other leg extending outwardly of the bow in a line intersecting the bow and projecting beyond the extremity of the first mentioned leg and members carried by the legs and arranged for coöperation with the extremities of the legs to produce a gripping action.

In testimony whereof, I affix my signature, in the presence of two witnesses.

ALFRED H. WAIT.
